THOMAS ALLATT, OF NEW YORK, N. Y., ASSIGNOR TO INTERNATIONAL CORK COMPANY,
OF BROOKLYN, NEW YORK, A CORPORATION OF NEW YORK.

DISK-SORTING MACHINE.

1,323,145.

Specification of Letters Patent. Patented Nov. 25, 1919.

Application filed March 28, 1919. Serial No. 285,871.

To all whom it may concern:

Be it known that I, THOMAS ALLATT, a subject of the King of Great Britain, and a resident of New York, in the county of 5 Richmond and State of New York, have invented certain new and useful Improvements in Disk-Sorting Machines, of which the following is a specification.

The present invention relates to a machine for sorting disks, such as for instance cork disks, the disks being carried upon a belt conveyer so that they may be inspected with a view to remove the defective or objectionable ones.

15 In machines of this type, the disks are fed by suitable means onto the conveyer, the attendant sitting next to the said conveyer examining and sorting the same as they travel past the seat. The disks are 20 continuously fed onto the conveyer and travel thereon in a mass, a few, say two or three, one on top of another, so that the attendant is compelled first to separate the disks in order to be able to inspect and 25 sort the same.

The main object of the present invention is to provide a simple and efficient means for separating and distributing the disks on the conveyer so that they move in a 30 continuous stream past the attendant but one deep, or in other words side by side, but never one on top of another.

With these and other objects in view which will more fully appear as the nature 35 of the invention is better understood, the same consists in the combination, arrangement and construction of parts hereinafter described, pointed out in the appended claims and illustrated in the accompanying 40 drawings, it being understood that many changes may be made in the size and proportion of the several parts and details of construction within the scope of the appended claims without departing from the 45 spirit or sacrificing any of the advantages of the invention.

One of the many possible embodiments of the invention is illustrated in the accompanying drawings, in which:—

50 Figure 1 is a vertical central section taken through a disk sorting machine constructed in accordance with the present invention; Fig. 2 is a section taken on line 2—2 of Fig. 1; Fig. 3 is a section taken on line 55 3—3 of Fig. 2, on a larger scale; Figs. 4 and

5 are vertical sections, on a larger scale, taken through the separating and distributing means; and Fig. 6 is a similar section taken through a detail of construction of said separating and distributing means. 60

In the drawings, the numeral 10 indicates a frame, supported by legs or standards 11. On this frame is mounted a screen 12, comprising a perforated plate 13, having side flanges 14. These side flanges are 65 connected with the frame 10 by resilient slats 15, to permit of a vibrating or reciprocating motion of said screen. The screen receives the cork disks from a receptacle 16, the means for supplying the disks from the said receptacle to the said screen being not shown, as they do not form part of the present invention. Vibrating or reciprocating motion is imparted to the screen by means of a crank 17 on a driving shaft 18, 70 the latter being rotatably mounted on the frame 10 and receiving motion from any suitable source of power, for instance by the intermediary of a belt 19 that runs over a pulley 20 on the said driving shaft. The 75 crank is connected by a, preferably, flexible rod 21 with the screen, one end of said rod being attached to a bushing 22 on the pin 23 of the crank, and the other end of said rod being fixed to the forward end of said screen, as clearly appears from Fig. 1 of the drawings. The screen is inclined toward its open front end, delivering the disks to a conveyer 24 of the belt-type. 80

The belt of the conveyer runs in the well-known manner over rollers, one of the same, denoted by the numeral 25, being shown in the drawings, receiving motion, from any suitable source of power, in the direction of the arrow shown in Fig. 1 of the drawings. 90 The acting portion of the belt, that is to say that part thereof which transports the disks from the screen forward, is disposed a slight distance below the screen and is arranged below the distributing and separating means 26. This means comprises a transverse bar 27, that is suspended from a transverse shaft 28 on the frame 10 by arms 29, the upper ends of said arms being hook-shaped, as shown at 30, and in engagement 95 with the shaft 28, thereby permitting of a swinging motion of the transverse bar 27, for a purpose hereinafter to be described. The bar 27 is held above the acting portion of the belt conveyer a distance which will 100 105 110

permit the disks to pass below the same on the belt conveyer side by side, but never one on top of another. The bar 27 is connected with the screen 12 by, preferably, resilient slats 27', so that it moves with the said screen.

With the bar 27 is associated a rake 31, including spaced teeth 32, which are loosely mounted upon a rod 33, that is oscillatably 10 journaled in lugs 34, the latter extending forward of and being attached to the bar 27. The teeth extend in rear of the bar 27, resting upon a transverse support 35, that is fixedly attached to levers 36, which, in turn, 15 are rigidly secured to the rod 33. To the free end of one of these levers is pivoted a connecting rod 37, the other end of which is fixed to a sleeve 38, that is drawn over a pin 39 on a bell crank lever 40, the latter 20 being fulcrumed at 41 to one of the side flanges 14 of the screen 12. To the bell crank lever is furthermore pivoted at 42 a link 43, the other end of which is pivoted at 44 to a flexible connecting rod 45, one end of 25 which is attached to a bushing 46 on the pin 47 of a crank 48, that is keyed or otherwise secured to the driving shaft 18. The other end of said flexible connecting rod is secured to a rearwardly inclined trough 49, that is 30 disposed below the screen 12 and suspended from the frame 10 by resilient slats 50.

The screen and trough move in opposite directions, the trough receiving the broken disks, chips, etc., from the screen and delivering the same into a receptacle 51 below the discharge end of said trough.

The teeth 32 of the rake are spaced apart, a distance that is greater than the diameter of the disks to be sorted, by suitable spacing 40 means, for instance in the form of sleeves 52, that are drawn over the rod 33. The free ends of the teeth extend downward toward the acting portion of the belt conveyer and in their lowermost position (Fig. 4) are 45 spaced from the said conveyer a distance that is, preferably, smaller than the thickness of the disks on the conveyer.

The operation of this device is as follows:—The disks, to be sorted, are supplied 50 from the receptacle 16 in either a continuous or intermittent stream onto the screen 12, which advances the same to the conveyer 24. As the conveyer moves in the direction shown by the arrow in Fig. 1 of the drawings, the disks are brought first within the 55 reach of the rake 31 and then in operative relation to the bar 27. This bar swings around the shaft 28 in unison with the screen 12, taking with it the rake, the teeth of 60 which, however, are actuated by the connecting rod 37 and the mechanism associated therewith. This mechanism is so timed that, when the bar 27 moves in the direction of the movement of the acting portion of the 65 belt conveyer, the said teeth are in their

lowermost positions (Fig. 4), in which the free ends of said teeth are disposed at a slight distance above the belt conveyer. When the bar 27 moves in the opposite direction, the connecting rod 37 tilts the levers 70 75 36, thereby lifting the said teeth into the position shown in Fig. 5 of the drawings, in which position they remain substantially to the end of the stroke of the bar 27, being lowered immediately before the said bar starts its movement in the direction of the movement of the acting portion of the belt conveyer. By so timing the movements of the bar 27 and the teeth of the rake, the said teeth, when in their lowermost positions, 80 move in the direction of the arrow shown in Fig. 4 of the drawings, spreading and distributing the disks within reach over the entire width of the conveyer, here and there removing disks from the lowermost layer. 85 They also have a tendency to keep the disks close to the bar 27, which allows the disks but one deep to pass under it on the conveyer, removing disks on top of the lowermost layer in its movement in the direction opposite to that of the acting portion of the belt conveyer.

The attendant inspects the disks in front of the spreading and distributing means, removing the imperfect or defective ones. Inasmuch as these disks are transported past the attendant's seat but one deep, the attendant is in a position to readily distinguish the defective disks without handling the same.

It is obvious that, while herein a specific means has been described for actuating the screen and trough, and the spreading and distributing means has been shown as being driven by the said screen and trough, any other means may be used for this purpose without departing from the invention, which lies mainly in the provision of a swinging frame having a transverse bar disposed at a distance from a belt conveyer that is somewhat greater than the thickness of the cork disks, in combination with a rake upon said frame having oscillatable teeth for the purpose specified.

The shaft 28 may be eccentrically mounted upon disks 53, said disks being seated in circular recesses 54 in the frame 10. By shifting the disks 53 in their respective recesses, the distance between the bar 27 and the belt conveyer may be adjusted at will.

What I claim is:—

1. In a machine for sorting disks, the combination with a conveyer adapted to receive a mass of undistributed disks, of a frame provided with a bar located transversely above said conveyer at a distance less than the thickness of two disks and greater than the thickness of a single disk, means for oscillating said frame and bar maintaining the latter transversely of said conveyer at a 125 130

distance less than the thickness of two disks, whereby the disks are caused to travel singly below said bar, and means carried by said frame for distributing the disks over the 5 width of said conveyer.

2. In a machine for sorting disks, the combination with a conveyer adapted to receive a mass of undistributed disks, of a frame provided with a bar located transversely 10 above said conveyer at a distance less than the thickness of two disks and greater than the thickness of a single disk, means for oscillating said frame and bar maintaining the latter transversely of said conveyer at a 15 distance less than the thickness of two disks, whereby the disks are caused to travel singly below said bar, and means carried by said frame extending rearwardly thereof for distributing the disks over the width of said 20 conveyer.

3. In a machine for sorting disks, the combination with a conveyer adapted to receive a mass of undistributed disks, of a frame provided with a bar located transversely 25 above said conveyer at a distance less than the thickness of two disks and greater than the thickness of a single disk, means for oscillating said frame and bar maintaining the latter transversely of said conveyer at a 30 distance less than the thickness of two disks, whereby the disks are caused to travel singly below said bar, and a rake carried by said frame for distributing the disks over the width of said conveyer.

35 4. In a machine for sorting disks, the combination with a conveyer adapted to receive a mass of undistributed disks, of a frame provided with a bar located transversely above said conveyer at a distance less than 40 the thickness of two disks and greater than the thickness of a single disk, means for oscillating said frame and bar maintaining the latter transversely of said conveyer at a distance less than the thickness of two disks, 45 whereby the disks are caused to travel singly below said bar, and a rake carried by said frame extending rearwardly thereof for distributing the disks over the width of said conveyer.

50 5. In a machine for sorting disks, the combination with a conveyer adapted to receive a mass of undistributed disks, of a frame provided with a bar located transversely above said conveyer at a distance less than 55 the thickness of two disks and greater than the thickness of a single disk, means for oscillating said frame and bar maintaining the latter transversely of said conveyer at a distance less than the thickness of two disks, 60 whereby the disks are caused to travel singly below said bar, a rake mounted upon said frame having oscillatable teeth, and means for swinging said teeth toward and away from said conveyer as said frame oscillates, 65 said teeth being brought toward said con-

veyer when said frame moves in the direction of travel of said conveyer and away from said conveyer when said frame moves in the opposite direction.

6. In a machine for sorting disks, the combination with a conveyer adapted to receive a mass of undistributed disks, of a frame provided with a bar located transversely above said conveyer at a distance less than the thickness of two disks and greater than 70 the thickness of a single disk, means for oscillating said frame and bar maintaining the latter transversely of said conveyer at a distance less than the thickness of two disks, whereby the disks are caused to travel singly below said bar, a rake mounted upon said frame having oscillatable teeth, and means for swinging said teeth toward and away from said conveyer as said frame oscillates, 75 said teeth being brought toward said conveyer when said frame moves in the direction of travel of said conveyer and away from said conveyer when said frame moves in the opposite direction, the space between two adjoining teeth of said rake being 80 greater than the diameter of an individual disk.

7. In a machine for sorting disks, the combination with a conveyer adapted to receive a mass of undistributed disks, of a frame provided with a bar located transversely above said conveyer at a distance less than the thickness of two disks and greater than the thickness of a single disk, means for oscillating said frame and bar maintaining 95 the latter transversely of said conveyer at a distance less than the thickness of two disks, whereby the disks are caused to travel singly below said bar, and a rake carried by said frame for distributing the disks over 100 the width of said conveyer, the distance between two adjoining teeth of said rake being greater than the diameter of an individual disk.

8. In a machine for sorting disks, the combination with a conveyer adapted to receive a mass of undistributed disks, of a frame provided with a bar located transversely above said conveyer at a distance less than the thickness of two disks and greater than the thickness of a single disk, 115 means for oscillating said frame and bar maintaining the latter transversely of said conveyer at a distance less than the thickness of two disks, whereby the disks are caused to travel singly below said bar, and a rake carried by said frame extending rearwardly thereof for distributing the disks over the width of said conveyer, the distance between two adjoining teeth of said 120 rake being greater than the diameter of an individual disk.

9. In a machine for sorting disks, the combination with a conveyer adapted to receive a mass of undistributed disks, of a bar ex- 130

tending transversely of said conveyer and swinging in the direction of the movement of said conveyer back and forth at a distance from the latter that is less than the thickness of two disks and greater than the thickness of a single disk, whereby the disks are caused to travel singly below said bar.

10. In a machine for sorting disks, the combination with a conveyer adapted to receive a mass of undistributed disks, of a bar extending transversely of said conveyer and swinging in the direction of the movement of said conveyer back and forth at a distance from the latter that is less than the thickness of two disks and greater than the thickness of a single disk, whereby the disks are caused to travel singly below said bar, and means coacting with said bar for distributing the disks over the width of the 20 conveyer.

11. In a machine for sorting disks, the combination with a conveyer adapted to receive a mass of undistributed disks, of a bar extending transversely of said conveyer and swinging in the direction of the movement of said conveyer back and forth at a distance from the latter that is less than the thickness of two disks and greater than the thickness of a single disk, whereby the disks 25 are caused to travel singly below said bar, and means coacting with and disposed in rear of said bar for distributing the disks over the width of the conveyer.

12. In a machine for sorting disks, the combination with a conveyer adapted to receive a mass of undistributed disks, of a bar extending transversely of said conveyer and swinging in the direction of the movement of said conveyer back and forth at a distance from the latter that is less than the thickness of two disks and greater than the thickness of a single disk, whereby the disks 40 are caused to travel singly below said bar, and means moving with said bar for distributing the disks over the width of the conveyer.

13. In a machine for sorting disks, the combination with a conveyer adapted to receive a mass of undistributed disks, of a bar 50 extending transversely of said conveyer and swinging in the direction of the movement

of said conveyer back and forth at a distance from the latter that is less than the thickness of two disks and greater than the thickness of a single disk, whereby the disks 55 are caused to travel singly below said bar, and means disposed in rear of and moving with said bar for distributing the disks over the width of said conveyer.

14. In a machine for sorting disks, the combination with a conveyer adapted to receive a mass of undistributed disks, of a bar extending transversely of said conveyer and swinging in the direction of the movement of said conveyer back and forth at a distance from the latter that is less than the thickness of two disks and greater than the thickness of a single disk, whereby the disks 65 are caused to travel singly below said bar, and a rake coöperating with said bar for 70 distributing the disks over the width of said conveyer.

15. In a machine for sorting disks, the combination with a conveyer adapted to receive a mass of undistributed disks, of a bar 75 extending transversely of said conveyer and swinging in the direction of the movement of said conveyer back and forth at a distance from the latter that is less than the thickness of two disks and greater than the thickness of a single disk, whereby the disks 80 are caused to travel singly below said bar, and a rake moving with said bar for distributing the disks over the width of said conveyer.

16. In a machine for sorting disks, the combination with a conveyer adapted to receive a mass of undistributed disks, of a bar extending transversely of said conveyer and swinging in the direction of the movement 90 of said conveyer back and forth at a distance from the latter that is less than the thickness of two disks and greater than the thickness of a single disk, whereby the disks are caused to travel singly below said bar, 95 and a rake disposed in rear of and moving with said bar for distributing the disks over the width of said conveyer.

Signed at New York, in the county of New York, and State of New York, this 100 11th day of February, A. D. 1919.

THOMAS ALLATT.
